(57) **CLAIM**

The ornamental design for a video laryngoscope, as shown and described.

DESCRIPTION

FIG. 1 is a front elevational view of a video laryngoscope showing our new design;

FIG. 2 is an enlarged front elevational view of the top portion of FIG. 1;

FIG. 3 is a rear elevational view of the video laryngoscope; FIG. 4 is an enlarged elevational view of the top portion of FIG. 3;

FIG. 5 is a left side view of the video laryngoscope;

FIG. 6 is a right side view of the video laryngoscope;

FIG. 7 is an enlarged view of the top portion of FIG. 5;

FIG. 8 is an enlarged view of the top portion of FIG. 6;

FIG. 9 is a top plan view of the video laryngoscope;

FIG. 10 is a bottom plan view of the video laryngoscope;

FIG. 11 is a front, right side perspective view of the video laryngoscope; and,

FIG. 12 is an enlarged view of the top portion of FIG. 11.
